UNITED STATES PATENT OFFICE.

GOVERNOR D. WARREN, OF DENVER, COLORADO.

HYDRAULIC AIR COMPRESSOR.

Application filed June 30, 1919, Serial No. 307,519. Renewed October 31, 1922. Serial No. 593,209.

To all whom it may concern:

Be it known that I, GOVERNOR D. WARREN, a citizen of the United States, residing at Denver, in the county of Denver and State of Colorado, have invented certain new and useful Improvements in Hydraulic Air Compressors, of which the following is a specification, reference being had therein to the accompanying drawing.

This invention relates to improvements in hydraulic air compressors, and is intended particularly for use in garages, dental and medical purposes, where it is especially desirable that compressed air be delivered free 15 from oil.

My improved compressor is operated from the city water power and is adapted to automatically supply air at varying pressures.

The primary object of my invention is to provide a hydraulic air compressor which will automatically maintain a predetermined pressure in a receiving tank from which the compressed air is taken for any 25 desired purpose or work.

In the accompanying drawings—

Figure 1 is a vertical central sectional view of an apparatus embodying my invention.

Fig. 2 is an inverted bottom plan view of the apparatus.

Fig. 3 is a vertical sectional view on the line 3—3 of Fig. 2.

Fig. 4 is a top plan view showing the 35 bottom construction in dotted lines.

Fig. 5 is a vertical sectional view on the line 5—5 of Fig. 4.

Fig. 6 is a partial horizontal sectional view of the bottom of my apparatus.

Fig. 7 is an enlarged vertical sectional view of the valve located in the top of the air compression cylinder.

Fig. 8 is a partial sectional view of a portion of the bottom valve construction.

Referring now to the drawings in which like numerals designate the same parts, 1 is a casing which has its lower half formed into a water cylinder 2, and its upper half formed into a relatively reduced air compression cylinder 3.

A double headed piston 4 is within the casing 1, the lower large piston head 5 operates in the cylinder 2 and the small piston head 6, operates in the cylinder 3.

Briefly stated, the water cylinder 2 receives its water from the city supply pres-

sure which forces the piston 4 upward to the position shown in Fig. 1, which compresses the air in the cylinder 3, and forces it outward past a suitable check valve 7 to 60 a receiving tank (not shown).

An automatic valve mechanism A is at the top of the cylinder 3, so that when the piston is in the position shown in Fig. 1, this valve mechanism is operated and 65 through a column of water 8 operates a valve mechanism B at the bottom of the cylinder 2, and places the lower end of the cylinder 2 in communication with a discharge opening 9, and closes a water admission opening 10, so that the water flows out of the cylinder 2 by gravity and the piston descends. When the piston reaches the bottom of the cylinder 2, it engages the valve mechanism B, which closes the discharge 70 opening 9 and opens the inlet opening 10, and the piston is forced upward, compressing the air in the cylinder 3, which air was admitted to the cylinder through an opening 11. It will be noted from the drawing that 80 the piston 4 fits loosely in the cylinder and by that means air passes through the opening 11' to the surrounding space and past the packing at the head of the piston as it moves downward. This operation is automatically repeated until the desired air pressure has been forced into the receiving tank, 85 not shown.

The automatic valve mechanism B at the lower end of the cylinder 2, comprises a 90 housing 12', in which there is a valve stem 12, having at one end a valve 13, and at its other end a valve 14. This housing 11' is provided with a central combined inlet and outlet port, which has its lower end 16 enlarged laterally to communicate alternately with the inlet and outlet ports 9 and 10. With the valve mechanism in the position shown in Fig. 5, the valve 13 has uncovered the upper end of the inlet port 10, so that 100 water will enter the lower end of the cylinder 2, and force the piston up. When the valve is moved to the opposite side from that shown in Fig. 5, then the inlet port 10 is closed and the outlet port 9 placed in communication with the port 15, so that the water in the cylinder 2 will flow therefrom into a water-pipe. The valve 13 moves in a cylinder construction 13' and the valve 14 moves in a cylinder construction 14'. 105 The valve 14 is of larger diameter than the valve 13, and has its inner end adapted to 110

seat against a wall or seat 17, as shown in Fig. 5, for the purpose of making a tight joint to prevent the inflowing water from passing by the valve 14.

- 5 This valve mechanism, just described, is operated by the city water pressure in that the valve cylinders 13' are in communication with the water supply, through ports 13² and 14², so that the valve mechanism is 10 moved back and forth automatically to admit and discharge water from the cylinder 2, and the water-pressure is alternately admitted to these cylinders by the movement of the piston 4.
- 15 The automatic valve mechanism A, at the top of the cylinder 3, comprises an inverted cup-shaped plunger 18, that is provided with a ground seat in the housing 19. Telescoping this cup-shaped plunger 18 is a 20 push-rod 20, movable through a packing 21. The cup-shaped plunger 18 is vertically movable in a cylinder 22, the upper end of which is in communication with the water column passage 8, and the lower end 25 23 of the water-passage 8 is in communication with the valve mechanism B, at the bottom of the cylinder. When the piston 4 reaches the position shown in Fig. 1, it forces up the push-rod 20 and carries with 30 it the plunger 18, and this plunger displaces the water in the cylinder 22, forcing it down through the passage 8. This column of water acts upon a valve 24 to force it up when the parts are in the position shown 35 in Fig. 1. In this position the water pressure is admitted to force the valves 13 and 14 to the left of the position shown in Fig. 5, so that the inlet port 10 is closed and the outlet port 9 is open. With the valves in 40 these positions, the water flows by gravity from the cylinder 2, and the piston drops. When the piston drops and reaches its lowest movement, it depresses the valve 24 and this depression of the valve 24 causes the 45 valves 13 and 14 to assume the position shown in Fig. 5, which closes the outlet port 9 and opens the inlet port 10.

When the pressure in the receiving tank (not shown) is equal to the water pressure 50 in the piston head 5, the operation of the compressor ceases, and the piston will stop in the position it happens to be when that pressure is reached. When, however, the pressure in the tank is lowered beyond the 55 water pressure on the piston head 5, the compressor again automatically begins to operate and replaces in the tank the pressure that has been withdrawn.

Referring now particularly to Fig. 3, the 60 valve 24 is cylindrical in form, having its ends closed by screw-plugs *a*, the top and bottom annular grooves *b* and *c* are connected with the interior of the cylindrical valve 24 by openings 26² and 26³, and 65 through this construction the said top and

bottom annular grooves *b* and *c* are placed in communication with each other. The lower annular groove *c* is in communication through an opening 26' with a port 26, which places the passage *c* in communication with the exhaust port or opening 9.

An intermediate groove *e* is formed in the periphery of the valve 24, and this groove is in communication with water under pressure through the ports 25, 25' and 25², and the intermediate groove *e* is out of communication with the exhaust port. With the valve 24 in the position shown in Fig. 3, exhaust is occurring through the ports 13², 26², valve 24, ports 26², groove *c* 80 and ports 26' and 26, while water under pressure is passing through ports 25, 25', 25², groove *e* and passage 14². By reference to Figures 4 and 5, it will be seen that the passage 13² communicates with the cylinder 85 13', and the passage 14² communicates with the cylinder 14'.

Fig. 8 is an enlarged view of the housing *f* for the valve 24, and this housing has the ports which have been referred to in connection with Fig. 3. In this figure is illustrated the valve 28, which connects with the lower terminal of the water column 8, the upper end of its stem 28' projects slightly above the top of the valve 24, when it is in its raised position. As a consequence, the valve 28 is engaged by the descending piston 4 in advance of the engagement of the valve 24, and the valve 28 is unseated in advance of the downward movement of the valve 24. By reason of this, the valve 28 allows water from the column 8 to pass up through its hollow stem 28', as 95 24 is being forced down to its lowest position. With the valve 24 in its lowest position, the cylinder 13' (of Fig. 5) is exhausting, while water pressure is being admitted to the cylinder 14', and the parts 100 assume the positions shown in Figure 5.

In Fig. 7, I show a very important feature 110 of my invention. In this figure the cup-shaped valve 18 has two telescoping members *g*, *h*, *i* and *k* and they are held together by the screws 27 and 29, and the plunger 18 is seated as described. The special value of 115 this member relates to its giving a minimum clearance between the piston and cylinder heads, when either working under load at the starting point, as described, or when the compressor is working without full load.

The operation of this part of my invention is as follows:—When the parts are in their normal positions, the pin 20 projects $\frac{5}{16}$ of an inch into the cylinder, and water flows into the chamber 22 through the opening *m* and fills the chamber. When the piston 4 is moving up with the light load, it pushes up on the pin 20 and part *i* much faster than the water can be forced from the cylinder or chamber 22, and as a consequence 120 125 130

the plunger 18 is moved up with the pin and part 2, and the plunger 18 moved off of its seat. The upward movement of the plunger 18 forces the water out of the cylinder or 5 chamber 22 into the column passage 8, and forces the water out of the lower end 8' of the passage 8 and against the lower end of the valve 24, forcing the valve 24 to its upward position. With the valve 24 up, the 10 water pressure is admitted into the cylinder 13', forcing the valves 13 and 14 to the reverse position from that shown in Fig. 5; and in this reverse position, the valve 14 opens the discharge port 9, and closes the 15 admission port 10. The water then flows from the cylinder 2, and the piston 4 descends, first engaging the valve 28 which relieves the valve 24 of pressure from the passage 8, and permits the piston to push the 20 valve 24 to its down position, which reverses the valves 13 and 14, which closes the discharge port 9 and opens the admission port 10. When, however, the piston 4 is working under load at or near the balancing point, 25 the upward movement of piston 4 will be very slow, taking it anywhere from a minute to an hour to reach its terminal after engaging the pin 20. During this time, the water will be forced from the chamber 22 through 30 the opening *m* and the pin 20 will reach the top of the chamber 22 in engagement with the plunger 18, and the water forced out of the chamber 22 of the plunger 18 is not sufficient to lift the valve 24 to a reversing position. When the pin 20 positively engages the plunger 18, the plunger 18 is unseated at its lower end about a 64th of an inch, which equalizes the area of the top and bottom ends of 18, and the residue of air in the 35 joint between the heads being much greater than the water pressure in passages 8, the plunger 18 is forced upward by the air, forcing the water from chamber 22, through the passage 8 and under the valve 24, lifting 40 it to reverse position, and reversing the valves 13 and 14 for the purpose described. The packings 21 carried by the plunger 18 provide sufficient friction to keep them at the place the piston 4 leaves them, thus preventing valve 24 from falling, and the valve 45 28 allows water to escape when pushed down by the piston 4 to permit the valve 24 to be pushed down by the piston. As soon as water under pressure is admitted into the 50 cylinder 2, water is introduced through the valve 28 to the passage 8, and forces the plunger 18 and valve 20 down to their seats ready to be operated by the piston as already described.

60 Having thus described my invention, what I claim and desire to secure by Letters Patent is:

1. A hydraulic air compressor, comprising a casing having a water cylinder at one end 65 and an air cylinder at the other end, a dou-

ble headed piston co-acting with the cylinders, a valve mechanism at the head of the water cylinder, a valve mechanism at the head of the air cylinder, said valve mechanisms controlled by the movement of the 70 piston for admitting and exhausting water to the water cylinder.

2. A hydraulic air compressor, comprising a casing having a water cylinder at one end and an air cylinder at the other end, a double headed piston co-acting with the said cylinders, a valve mechanism in the head of the water cylinder for controlling the admission and discharge of water thereto, said valve mechanism adapted to be actuated by 75 the adjacent head of the piston.

3. A hydraulic air compressor comprising a casing having at one end a water cylinder, and at its other end an air cylinder, a double headed piston therein co-acting with the 85 said cylinders, a valve mechanism in the head of the water cylinder to control the admission and discharge of water to said cylinder, a valve mechanism at the head of the air cylinder, a column of water operatively connecting the two valve mechanisms, the piston heads adapted to respectively move the valve mechanisms to control the admission and discharge of water in the 90 water cylinder.

4. A hydraulic air compressor, comprising a vertical casing having at its lower portion a water cylinder and at its upper portion an air cylinder of relatively smaller diameter, a double headed piston co-acting with the 100 said cylinders, a valve mechanism in the head of the water cylinder controlling the admission and discharge of water thereto, a valve mechanism in the head of the air cylinder, a water containing passage connecting the 105 valve mechanisms, the air piston head moving the valve mechanism in the head of the air cylinder to cause the water column to act on the valve mechanism in the head of the water cylinder, a movable member of 110 the last said valve mechanism adapted to be engaged by the water cylinder and piston head to move it, whereby water is alternately and automatically admitted to and discharged from the water cylinder.

5. A hydraulic air compressor, comprising a vertical casing having a water cylinder at its lower portion and an air cylinder at its upper portion, a double headed piston working in said cylinders, a valve mechanism in 120 the head of the water cylinder adapted to be moved by the water piston head, a valve mechanism in the head of the air cylinder comprising a cup-shaped valve and a telescoping push-rod adapted to be actuated by the air piston head, and a water column operatively connecting the said valve mechanisms.

6. In a construction such as defined in claim 3, the valve mechanism for the head 130

of the air-cylinder comprising a cylinder in communication with the column of water, a cup-shaped valve in the cylinder having a small interior communication with the cylinder and a piston within the cup-shaped valve, whereby a relatively quick movement of the piston will move the valve, as described.

7. In a construction such as set forth in claim 3, the valve mechanism for the head of the air-cylinder, comprising a cylinder and valve therein, having a small interior communication with the cylinder, the cylinder in communication with the water column, whereby water will flow into the cup-shaped valve, a piston within the cup-shaped valve adapted to be actuated by the compressor piston, whereby a relatively fast movement of the valve piston will move the valve through the medium of the water therein and a slow movement of the piston forces the water out of the valve without moving it until the piston reaches its limit of movement in the cup-shaped valve.

25 8. In a construction such as defined in claim 3, the valve mechanism for the head

of the compression cylinder, comprising a cylinder in communication with the water column, said cylinder having a valve seat at its lower end, a cup-shaped valve within the cylinder and adapted to close the said valve when in its lower position, the cup-shaped valve having a small interior communication with the cylinder and column of water, a piston within the valve, whereby a relatively fast movement of the said piston will move the valve through the medium of the water in the valve, and a slow movement permits the escape of the water from the valve and lifts it from its seat, thus establishing communication with the compression cylinder, whereby the air therein forces the valve to its upper position.

9. In a construction such as set forth in claim 8, the valve and piston having friction packings for the purpose of normally maintaining them in their upward positions until forced downward by water pressure.

In testimony whereof I hereunto affix my signature.

GOVERNOR D. WARREN.
